Application September 22, 1932, Serial No.
634,384, and in Great Britain October 14,
1931

5 Claims. (Cl. 26—46)

This invention refers to apparatus or machines for applying moisture to fabrics for cooling and conditioning purposes i. e. for restoring moisture to fabrics after they have passed through drying, finishing and like operations.

The invention refers in particular to cloth cooling and conditioning machines of the kind wherein the cloth to be treated is caused to traverse in a zig-zag path through a closed chamber, while 10 water is carried upwards between the adjacent vertical stretches of the cloth by absorbent endless belts, the latter dipping into troughs of water. The power required to drive these belts is considerable. Moreover, the belts are only arranged 15 between alternate stretches of the cloth.

The main object of the invention is to dispense with the belts, and to provide an improved construction of stationary moisture-distributing apparatus which allows of being arranged between 20 either alternate or successive stretches of the cloth. A further object is to provide moisture-distributing units which by being non-absorbent or practically non-absorbent, allow of being only superficially wetted and thereby ensure of a more 25 rapid evaporation of the water and the more rapid and effective moistening of the cloth.

According to the invention, the improved machine comprises a large outer casing, similar to that of the known machine, wherein are arranged 30 the usual sets of guide rollers, upper and lower, for the cloth. At each end of the casing are openings for the admission and exit of the cloth. In the upper part of the machine and between adjacent vertical stretches of the cloth are water 35 troughs, while extending downwards from said troughs are slab-like members, made of wood, asbestos cement, or other practically non-porous material, the area of the structure being similar to that of the adjacent stretches of the cloth. 40 The slab-like members, hereinafter called the moistening units, are supported on channel bars, which besides supporting the units, serve to convey any surplus water away to conduits near the sides of the machine.

45 Water is supplied to the troughs by small branch pipes from a supply pipe common to all, which at one end is closed and at or near the other end is furnished with a control cock.

With water delivered to the troughs, it finds its 50 way down the two opposite sides of the units in the form of a film, the whole of the side surfaces of the units being wetted and with such surfaces in proximity to the cloth and the cloth hot and dry, the water becomes rapidly evaporated and 55 absorbed by the cloth.

In the accompanying drawings:—

Figs. 1 and 1a collectively illustrate a side elevation (with the near side enclosure panels removed), and Fig. 2 a cross sectional elevation (with side enclosure panels in position) of a machine constructed according to the invention. 60

Figs. 3, 4 and 5 are enlarged cross sections (partly broken away) of various constructions of moistening units that may be used in the machine. 65

Referring to Figs. 1 and 2, the machine comprises a large rectangular chamber A built up of channel-iron members a, a and removable sheet-metal panels b, b, the channel-iron forming a framework and the sheet-metal panels closing in 70 the spaces of the framework and forming the walls of the chamber. The panels are a tight fit in the framework. In the upper part of the chamber are guide rollers c, rotatably journaled in bearings c¹ depending from the upper side 75 channel members of the chamber A, see Fig. 2. In the lower part of the chamber are further guide rollers d journaled in bearings d¹, carried by the lower side channel members. The rollers of each set are equally spaced apart, and those 80 in one row lie in planes intermediate of those in the other row.

The cloth to be cooled and conditioned (moistened) is admitted to the chamber A through a slot or elongated opening in one of the end 85 walls or covers, and in its passage through the machine passes over rollers c and under rollers d, finally leaving the chamber through a slot or elongated opening in the opposite end wall or cover of the chamber, see Fig. 1. The cloth 90 before entering the machine may pass through an arrangement of guider bars c² and over a set of rollers c³, to remove creases and cause it to pass to the machine in a flat condition.

Between the vertical stretches of the cloth are 95 mounted the moistening units, each of which comprises a trough or duct at its upper end (near the rollers c) and a vertically disposed part or parts of large surface area.

In the example shown in Fig. 3, the moistening unit consists of a wood board e, with the trough or duct e¹ cut in the top edge of the board. In the floor of the trough or duct and at intervals along the said floor are inclined holes, through 100 which water from the trough may flow on to the surfaces of the board, and so wet such surfaces. To prevent a too rapid discharge of the water, and also prevent choking, the holes in the floor of the trough may be fitted with tubes 105 110

e^2 and through the tubes may pass lengths of cotton wick e^3 .

To help to ensure even distribution of the water, the board e is provided with ledges or shoulders e^4 extending the full width of the board and acting as sills or weirs.

In the example shown in Fig. 4, the moistening unit also consists of a wood board e , while a metal trough or duct f is fitted to the top edge 10 of the board, which is shouldered to receive the duct, as well as to form the horizontal ledges for the water to flow along as it is conveyed there-to by the lengths of cotton wick f^1 .

In the example shown in Fig. 5, the moistening 15 unit consists of two large sheets g^1 , g^1 of asbestos cement, wood or the like, spaced apart by wood packing bars h , h and held together at intervals by screws i , i . Above the top of the boards is horizontally mounted a metal pipe j with rows of holes k along each side, and with a hole l in its top face, and near one end. Threaded through each pair of opposite holes k and extending below a rod m within the pipe j is a length of cotton wick n , the loose ends of 20 which rest on the top edges of the sheets g^1 , g^1 . This last described construction of moistening unit is the one shown applied in Figs. 1 and 2.

In each example, the moistening unit rests upon the channel bars o , extending across the 30 machine and supported by the further longitudinal channel bars p , p .

For further supporting the moistening units, adjustable steady pins or stay members g^2 are provided, which engage angle-iron slippers g^3 embracing the edges of the unit, see Fig. 2. Wire lashings g^4 may be used to help to hold the slippers to the unit.

Extending along the machine is a water-supply pipe r , and from such pipe extend a plurality of small bore tubes r^1 , one for each moistening unit. The free end of each tube r^1 is bent downwards and dips into a cup i^1 , opening 40 at its lower end into the pipe j of the unit (see Fig. 2). When the constructions of moistening units shown in Figs. 3 and 4 are used, the tubes r^1 extend down into the trough (Fig. 3) or connect with a hole in the end of the trough (Fig. 4).

Said water supply pipe r is closed at one end (see Fig. 1) and terminates at such end inside 50 the machine, while at its other end, which extends outside the machine, the pipe is fitted with a control cock r^2 .

To further help to reinforce the moistening units, especially when made of asbestos cement boards, a metal frame g^5 may be fitted to each 55 face of the unit, see Fig. 2.

The several rollers c , c are provided with 60 duplex chain wheels s and are driven through a shaft t common to all from any suitable source of power.

The ends of the channel bars o open into the channel bars p , see Fig. 2, while from each of the latter extends a T pipe u , leading to a sump or culvert v .

65 The operations of the machine are as follows:—With a web of cloth threaded through the machine (which is facilitated by removing some of the side panels of the chamber A), and the rollers c and d set in motion, the cloth travels through the machine. The control cock r^2 is then (or previously) opened, whereupon water flows into the ducts or troughs of the respective moistening units, which finding its way through the openings in the troughs and regulated by 70 the wicks, flows in the form of a film down the

two opposite faces of the units. Owing to the heat of the cloth and the proximity of the vertical stretches of the cloth to the films, the water becomes taken up by the cloth, each traverse of the cloth between the moistening units enabling all parts of the cloth and on both sides reaching the final roller to receive and absorb the desired degree of moisture.

In the example shown in Fig. 1, there is a moistening unit next each side of the cloth as it passes up or down, but there may be a moistening unit only between alternate stretches of the cloth.

By regulating the control cock r^2 , the amount of water supplied to the ducts or troughs and therefore to the cloth, may be varied, and such variation may also be determined by the speed of the cloth.

The wood employed in the construction of the moistening units will preferably be coarse grained so that its surface will be somewhat rough and produce a rippling effect on the film of water flowing down the unit. Alternatively, large mesh wire netting g^6 (see Fig. 2) may be applied to each face of the board, which while breaking up the film helps to prevent the cloth touching the board.

What I claim is:—

1. A cloth cooling and conditioning machine of the kind comprising a large rectangular chamber, and guide rollers in the upper and lower parts of the chamber for conveying the textile material through the chamber, characterized by stationary moistening units between the vertical stretches of the textile material, each unit comprising a water conduit, and depending vertically from said conduit, a non-porous slab-like member, down the opposite sides of which water from the conduit flows film-fashion, means for conveying water to each trough and from the trough to the slab-like structures, a channel-shaped cross-bar below each slab-like unit, and means for supporting the cross-bars and conveying any excess of water away from the machine.

2. In a cloth cooling and conditioning machine as claimed in claim 1, stationary moistening units each consisting of a flat wood board, and a water conduit along its top edge, the conduit having holes in its side walls for water to flow through and pass down each face of the board-like member, the units being supported by channel-shaped cross bars, which in turn, rest upon like channel-shaped bars running lengthwise of the machine.

3. In a cloth cooling and conditioning machine as claimed in claim 1, stationary moistening units, each consisting of a rigid structure composed of wood, asbestos-cement, or like material, and also consisting of a pipe-like conduit above its top edge with perforations in its upper part, and lengths of wick threaded through said perforations and resting at their free ends on the top of the said boards.

4. In a cloth cooling and conditioning machine as claimed in claim 1, a stationary moistening unit having horizontal ledges or shoulders near its upper end and on opposite sides, on to which water from the trough flows, the ledges or shoulders forming sills or weirs over which the water flows, prior to flowing down the faces of the unit.

5. A machine in which moisture is applied to textile material while passing through the machine, comprising a large rectangular chamber composed of channel-iron members and sheet metal panels for closing in the spaces of the frame and forming the walls of the chamber, some of the panels being removably fitted to the frame with removable side panels, sets of guide

rollers in the upper and lower parts of the chamber for conveying the material in a zig-zag path through the machine, means for driving one set of the rollers, stationary moistening units between the vertical stretches of the material, each comprising a water conduit, and a slab-like member composed of wood, asbestos cement or like

practically non-porous material depending vertically below the conduit, means for conveying and controlling a supply of water to the conduits, means for supporting the units, and means for conveying away any excess of water from the units. 80
